Attorney.

UNITED STATES PATENT OFFICE.

CHARLES H. FAWCETT, OF INDEPENDENCE, IOWA.

LICENSE-HOLDER FOR MOTOR-VEHICLES.

1,330,067.

Specification of Letters Patent. Patented Feb. 10, 1920.

Application filed February 24, 1919. Serial No. 278,924.

To all whom it may concern:

Be it known that I, CHARLES H. FAWCETT, a citizen of the United States of America, and a resident of Independence, Buchanan county, Iowa, have invented certain new and useful Improvements in License-Holders for Motor-Vehicles, of which the following is a specification.

My invention relates to improvements in license holders for motor vehicles, and the object of my improvement is to provide a holder for receiving a license card, or the like, supplied with means for propelling the card to and fro, and furnished with means for defacing the card operable only at the time of propelling the card out of said holder.

This object I have accomplished by the means which are hereinafter described and claimed, and which are illustrated in the accompanying drawings, in which Figure 1 is a plan view of my improved device as closed and sealed with a license card mounted therein. Fig. 2 is a horizontal section 25 of the device, with parts broken away, taken on a plane immediately below the transparent closure for the top opening of the casing. Fig. 3 is a vertical longitudinal section, taken on the broken line 3—3, of Fig. 2 and looking in the direction of the arrow. Fig. 4 is a vertical longitudinal section, taken on the broken line 4—4, of Fig. 2, and looking in the direction of the arrow. Fig. 5 is a vertical cross section of the casing and its contents, and partly an end elevation thereof, the section being taken on the broken line 5—5, of Fig. 2. Fig. 6 is an enlarged detail view of the defacing means for mutilating the card.

Similar numerals of reference denote corresponding parts throughout the several views.

It is my purpose to supply a holding device for a card, such as a license card, for motor vehicles, which includes means for preventing the withdrawal of a card without permanently defacing it, thus making it unfit for further use, but which is prepared to receive a newly-issued card after the other has been removed, the holding means being so sealed and safeguarded in its parts as to prevent tampering with the inclosed propelling and defacing mechanism.

In Fig. 1, a license card 1 is shown 55 closed in my improved holding means, and contains the printed designations, signature,

and other data, such as is appropriate for the purpose.

The holding device comprises a casing 2, a base-plate 13 therefor, and certain propelling and defacing mechanism. The casing 2 is of rectangular form, having an open bottom, supplied with side flanges 3 and end flanges 4 extending horizontally therefrom. The base plate 13 is of rectangular form, of somewhat larger dimensions than said casing, and has on its sides and ends, respectively, rectangular extensions or projections 5 and 6 which are bent upward vertically, as shown in full lines in Fig. 2, 70 the dotted lines in said figure displaying the outline of said base-plate when developed on a plane surface. In assembling these parts, the casing 2 is placed upon the base-plate within the raised projections 5 and 6, 75 and then strips of fusible solder 9 are placed lengthwise along the side and end flanges 3 and 4 of the casing. The base-plate projections 5 and 6 are then folded over upon and in contact with said strips of 80 solder, and sufficient heat applied to fuse the solder, thereby firmly uniting these parts together.

One end of the casing has a slot 12 for the passage of the card 1. Within the casing is 85 fixed the horizontal shelf 11 which extends only part of the way toward the end of the casing containing said slot. A plate of glass or other transparent material 7 is mounted in the upper part of the casing fixedly, and 90 closes a relatively large rectangular opening 8 in the top of the casing. The license card 1, after being passed into the casing through the slot 12, is positioned between the shelf 11 and the glass plate 7. Orifices 10 may be 95 formed in the engaged parts of the casing end flanges and the inclosing base-plate parts, to receive bolts or other fastening means to secure the device to a supporting body.

The card propelling-means and defacing-means are both located below the card 1 to work in the open space to the right of the shelf 11.

The card propelling-means comprises a 105 two-part longitudinally-corrugated roller 16—17, having reduced ends rotatably mounted in semi-cylindrical bearings in blocks 14 fixed on opposite inner side-walls of the casing, thus allowing some vertical 110 displacement to the roller under the impulsion of bar-springs 15 which are secured at

one end to said blocks, and pass under and support the roller. These springs tend to retain the roller in close frictional engagement with the under face of the card, so that 5 the longitudinal corrugations or ribs, or other frictional corrugations may propel the card when the roller is rotated in either of opposite directions by any means, such as a screw-driver inserted through an opening 10 21 in the casing into a socket 20 in the abutting end of the roller. The roller is formed in two alined parts 16 and 17 for convenience of manufacture, the part 17 having formed on its inner extremity an 15 integral star-toothed ratchet-wheel 18 and a terminal screw 19 to enter an interiorly-threaded socket on the abutting extremity of the part 16.

When a card is pushed through the slot 20 12 far enough to pass between the roller 16—17 and the plate 7, and the roller then rotated to the left, the card is drawn into the casing completely, where it becomes plainly visible through the glass plate 7, 25 as shown in Fig. 1.

To prevent a reverse rotation of the roller from ejecting the card in its original undefaced condition, and thus defeat re-use or illicit alterations thereon, I have provided 30 mechanism for defacing or splitting the card into separated parts. This comprises a sharp-edged rotatable cutter 25 mounted in bifurcations 24 of a rock-body pivotally mounted on a fixed horizontal shaft 22 and 35 having on its opposite end a pointed detent or pawl 23. The cutter bears against the card opposite an interspace of blocks 27 fixed on the casing top. A forked leaf-spring 26 has its forked parts engaged under 40 the bifurcations of the body 24 and serves to yieldingly retain the cutting-wheel 25 in its upper position. The single-pointed and two-beveled end of the detent 23 engages the teeth of the star-ratchet 18 to work clicking 45 thereover in either of opposite directions, and as it has but a small area of contact with the teeth of said ratchet, it releases a tooth when the tooth is rotated a short distance. It will be seen, that when the roller 16—17 50 is rotated to the left to propel a card into the casing, the successive engagements of the ratchet-teeth keep the detent point raised, which causes a depression of the cutting-wheel 25 out of engagement with the card, 55 while placing the springs 26 under tension. When the roller is rotated in an opposite direction, the ratchet-teeth depress the detent 23 thus elevating the cutting-wheel 25 aided by reaction of the springs 26 to force 60 the sharp edge of the wheel through the card, whereby as said card is continuously propelled outwardly through the slot 12, it is severed into equal parts by the cutting-wheel.

65 I have shown in Fig. 6, additional card

defacing-means for scratching or marring the upper or print-bearing face of said card. The means comprises a pair of pointed fingers 30 pivotally mounted on fixed rods 29, their pointed extremities inclined toward 70 the upper surface of the card to ride thereover without defacing the card when the card is being propelled into the casing. Small helical compression-springs 28 may be employed to exercise yielding pressure upon 75 these fingers, and the fingers may have stops 32 to engage blocks 31 to limit their movement in one direction. When the card is propelled toward the slot 12 outwardly the points of the fingers catch in and mar the 80 printed surface, leaving ineradicable marks thereon.

Various alterations or changes may be effected in the details of my said device, without departing from the principles of 85 the invention.

Having described my invention, what I claim as new, and desire to secure by Letters Patent, is:

1. In a device of the character described, 90 a closed casing having a slot, propelling-means mounted in said casing to propel a card toward or from said slot, defacing-means mounted in said casing to move to and from said card, and means actuated by 95 said propelling-means when the latter moves said card in either of opposite directions to shift said defacing-means into or out of defacing engagement with the card.

2. In a device of the character described, 100 a closed casing having a slot, propelling-means mounted in said casing adapted to move a card within the casing toward or from said slot, defacing-means mounted in said casing to move to and from said card, 105 resilient means operating yieldingly upon said defacing-means to normally retain it in defacing engagement with the card, and means actuated by said propelling-means when the latter moves said card in either of 110 opposite directions to shift said defacing-means into or out of defacing-engagement with the card.

3. In a device of the character described, 115 a closed casing having a slot, propelling-means mounted in said casing adapted to move a card within the casing toward or from said slot, a cutting blade mounted in said casing to move to and from said card, means actuated by said propelling-means 120 when the latter moves said card in either of opposite directions to shift said cutting blade into or out of cutting engagement with the card, and spaced fixed abutments on the opposite side of the card from said cutting 125 blade with their interspace opposite the blade.

4. In a device of the character described, 130 a closed casing having a slot, resiliently-controlled propelling-means mounted in the

casing to propel a card therein in either of opposite directions, resiliently - controlled defacing-means for said card, and a movable device on which said defacing-means is 5 mounted operable by movable engagement with said propelling-means to shift the defacing-means into or out of engagement with said card.

5. In a device of the character described, 10 a closed casing, a card movably supported therein, propelling-means for moving the card to and fro, and defacing-means operatively engaged with said propelling-means to be shifted by the propelling-means into or 15 out of defacing-engagement with said card when the latter is moved by the propelling-means in opposite directions.

6. In a device of the character described, 20 a closed casing, a card movably supported therein, propelling-means for moving the card to and fro, cutting-means operatively engaged with said propelling-means to be shifted by the propelling-means into or out 25 of cutting engagement with said card when the latter is moved by the propelling-means in opposite directions, and defacing-means 30 movably supported in said casing to deface said card when the latter is moved in one direction and to yield relative to the card when the latter is moved in an opposite direction.

7. In a device of the character described, 35 a closed casing, a card movably supported therein, propelling-means mounted movably in said casing to shift said card to and fro, and resiliently - controlled defacing - means 40 movably mounted in said casing to deface the card when the latter is moved in one direction and to yield relative to the card when the latter is moved in an opposite di- 45

rection.

8. In a device of the character described, 45 a closed casing having a slot, a card movable into or out of said casing through said slot, a propelling friction-roller in said casing 50 mounted rotatably to engage and propel said card in either of opposite directions, a ratchet on said roller, a pivoted frame having a detent movably meshing with teeth on said ratchet for disconnectible engagement 55 therewith when the ratchet is rotated in either of opposite directions, a cutting-blade mounted on said frame, and resilient-means bearing on said frame to yieldingly force it toward said card, said frame and blade being moved toward or from said card by engagements of said detent with said ratchet when the latter is rotated in opposite directions.

Signed at Waterloo, Iowa, this 18th day 60
of Feb., 1919.

CHARLES H. FAWCETT.
